Fig. 1.

Fig. 2.

This technical drawing illustrates a complex mechanical assembly, possibly a valve or pump component. The drawing is labeled with numerous part numbers, including 44, 69, 67, 20, 66, 79, 78, 77, 15, 80, 19, 65, 70, 12, 63, 64, 61, 62, 55, 60, 58, 40, 71, 56, 50, 54, 57, 81, 76, 21', 22, and 1.N.S. The assembly features a central rectangular body (part 70) with a ribbed base (part 76). A long, thin rod (part 71) extends from the right side. On the left side, there is a circular component (part 44) with a ribbed outer edge and a central hole. Various other parts are shown, including a small circular component (part 63) attached to the central body and a small rectangular component (part 1.N.S.) located at the bottom center.

CONDUCTOR-INSULATOR CLAMP

David C. Hubbard, Centralia, Mo., assignor to
 A. B. Chance Company, Centralia, Mo., a corporation of Missouri

Application December 11, 1941, Serial No. 422,476

19 Claims. (Cl. 174—172)

The present invention relates to conductor-insulator clamps, and is particularly concerned with the provision of an improved securing device for securing line conductors to line insulators in such manner that the conductors may be detached and attached at will with a minimum amount of labor and without changing the securing devices.

One of the objects of the invention is the provision of an improved conductor-insulator clamp which is provided with latching means so constructed that there is practically no possibility of the clamp being loosened by vibration or the strains to which the conductors or insulators of a transmission line are ordinarily subjected.

Another object of the invention is the provision of an improved conductor-insulator clamp of the class described which is adapted to be secured to the insulator in a plurality of different positions so that its actuating or securing devices may be arranged for convenient engagement with a clamp stick or other line tool.

Another object of the invention is the provision of an improved conductor-insulator clamp adapted to effect a resilient clamping action for securing a conductor to a line insulator having threaded means for regulating the pressure of engagement of the clamp with the conductor and a latching device for positively preventing the release of the threaded means.

Another object of the invention is the provision of improved forms of conductor-insulator clamping devices which are adapted to be quickly and firmly secured against loosening of the conductor or device from the insulator.

Another object of the invention is the provision of an improved conductor-insulator clamping device which is sturdy, simple, capable of being manufactured at a low cost, and adapted to perform its functions for a long period of time without any necessity for repair or replacement of parts.

Another object of the invention is the elimination of the use of the usual copper tie wires which must be installed new each time a conductor is placed or replaced on an insulator.

Another object is the saving of time and expense in the applying and removing of such tie wires from the conductor during maintenance work and to increase the safety of the system with respect to operators or line men on account of the fact that the conductors may be freed from or anchored to an insulator with hot line tools with greater safety when the present invention is employed.

When tie wires are being removed from an energized line by means of the line tools which are called hot sticks, these tie wires present a considerable length of energized wire which it is difficult to handle in a safe manner. The extending length of energized wire of a tie wire necessarily waves about through the air during the process of unwinding the tie wires from the conductors. Thus at frequent intervals it is desirable or necessary to stop untying operations long enough to use a pair of insulated connectors to cut off the unraveled length of the wire.

Even with this precaution, extreme care is necessary to avoid striking other objects of the unraveling tie wire. In the case of double arm construction there are arming bolts employed at the extreme end of the arms, and in some cases these bolts are grounded. Contact with such bolts would short circuit the line being worked on, causing a dangerous condition to the line-man and defeating the purpose of operating on the line without affecting its condition of energization.

This is only one of the special difficulties that may be encountered in the process of unwinding such tie wires, and these difficulties are eliminated when the present clamping arrangement is used.

Other objects and advantages of the invention will be apparent from the following description and the accompanying drawings, in which similar characters of reference indicate similar parts throughout the several views.

Referring to the two sheets of drawings accompanying the specification,

Fig. 1 is a fragmentary plan view of a line installation showing the application of the present conductor-insulator clamp in such manner that the cross arm will not interfere with the use of a clamp stick for engaging the eye of the clamping device;

Fig. 2 is a side elevational view of a conductor-insulator clamp embodying my invention;

Fig. 3 is a similar view of a modification;

Fig. 4 is a top plan view of the device of Fig. 3;

Fig. 5 is a top plan view of the device of Fig. 2.

Referring to Fig. 1, 10 indicates a line pole

11 carrying a plurality of insulators, one of which

is indicated at 12.

The line conductor is carried by the insulator

12, and is indicated by the numeral 31, and 14

indicates the conductor-insulator clamping device

embodying my invention.

55 Referring to Figs. 2 and 5, the conductor-in-

sulator clamp is here shown in greater detail. It preferably comprises a conductor engaging arm 15, which is pivotally mounted upon a collar 16 carried by the insulator 12. It also comprises a threaded member or extension 17 of the arm 15, which is provided with a threaded member or nut 18 for securing the arm 15 in clamping position.

The present device is preferably adapted to be used with standard line insulators of the type used on high voltage transmission lines, but it may, of course, be employed with any type of insulator on any type of line.

The insulators above-mentioned are usually provided with a member 19 having a transverse conductor-receiving groove 20 in the upper face 21 of the head 19.

Below the head 19 there is located a tie wire groove 21', and the insulator usually has one or more skirts 22. The clamping device is provided with means for permanently securing it to the insulator 12, such as, for example, the clamping collar, which may consist of two similar parts.

In the embodiment illustrated (see Fig. 5) the clamping collar 16 consists of a pair of similar parts, which may be constructed of cast metal, each of which has a semi-circular portion 23 and a pair of radially extending flanges 24, 25 at each end.

While the portion 23 has been described as semi-circular, it preferably embraces less than half the periphery of the insulator groove 21 so that the flanges 24, 25 may be suitably spaced from each other to be secured together by the bolts 26, 27.

For this purpose the flanges 24, 25 are each provided with the bolt apertures 28, 29, the apertures being in registry in the flanges 24 and in the flanges 25. A nut 30 on each of these bolts and a spring washer 31 are used for urging the two half circular members 23 together to clamp them on the insulator in the groove 21.

This collar 16 is preferably a relatively permanent attachment on the insulator, as it may be placed on the insulator at the time the line is constructed, and may remain on the insulator until the line is entirely dismantled; but the device is preferably provided with means for securing the conductor in such manner that the conductor can be quickly removed or reattached to the insulator.

This means is preferably in the form of a pivoted lever 15, which may comprise a strip or bar of metal formed with a cylindrical bearing portion 32 at its right end in Fig. 5 for pivotal mounting on the bolt 26.

In order to provide a sufficient body of material for this purpose the arm 15 may comprise a strip of metal which is substantially wider than its thickness so that it can be bent in the direction of its smallest dimension about the bolt 26.

At its opposite end the arm 15 (Fig. 5) is provided with a longitudinally extending slot 33, separating the two bearing portions 34, 35, which carry the pintle 36 in the form of a rivet. The rivet 36 may pivotally support the shank 17 of a screw bolt having a threaded portion 38 for engagement with a threaded member 18.

The pivotal mounting of the bolt 17 at 36 on the arm 15 permits an independent adjustment of the position of the bolt 17 so that its threaded member 18 may engage flatly against the edges of the retaining flanges 24 on the collar 16.

The flanges 24 on the collar 16 project laterally and substantially parallel to each other, and are secured together by the bolt 27, and they preferably project diagonally upwardly beyond the

bolt 27 to serve as retaining flanges for the threaded member 18.

The flanges 24 are spaced sufficiently to receive the bolt 27 between them, and their lower edges 39 engage the flat or plane face 40 of the threaded member 18.

The threaded member 18 may comprise a cast metal member having a substantially cylindrical body portion 41, which is provided with the plane end surface 40 and with an axial threaded bore 42.

To save material, there may be an opening formed at 43 in the body 41, into which the bolt 17 projects. The body 41 is preferably provided with an eye portion 44 formed by an integral toroidal extension, the opening of which is indicated at 45. The eye 45 is preferably of the same size as the eye of a standard hot wire clamp so that it may be engaged by ordinary clamp sticks, but in some embodiments of the invention the eye may be of larger size, where it is not intended to be received in the socket of a clamp stick.

In order to secure the threaded member 18 against any rotative motion, its plane surface 40 is preferably provided with one or more axially projecting ribs 46, 47.

These ribs may be of substantially rectangular cross section, but they are preferably slightly tapered at their sides 48 so as to facilitate their camming the threaded member away from the retaining flanges 24 when the threaded member is actuated by a clamp stick.

The ribs 46, 47 are located between the flanges 24 when the device is in clamping position, and act as positive stops for engaging the flanges 24 and preventing rotation of the threaded member 18 except by the application of a predetermined rotative force with a clamp stick or other tool.

Referring to Fig. 3, in this embodiment the shank of the bolt 17 is not threaded at its lower end, but is provided with a transverse pintle, preferably in the form of a rivet 49.

The eye 45 has its body portion 50 bifurcated by means of a longitudinal slot 51, which separates it into two flanges 52, 53. The flanges 52, 53 are provided with the apertures 54 for receiving the rivet 49, whereby the body is pivotally mounted on the bolt 17, which is in the nature of a connecting rod.

The slot 51 preferably extends only into the top, and not all the way through the body, with sufficient clearance to permit a pivotal movement of the body 50 on the connecting rod 17, and with a stop surface 55 engaging the lower side 56 of the connecting rod 17 when the parts are in the position of Fig. 3.

Thus the eye member 57 is pivoted on the rod 17 for a limited amount of pivotal movement, and when it reaches the position of Fig. 3, the eye member 57 is adapted to exert a downward pull on the rod 17 to pivot it counterclockwise.

The side flanges 52, 53 of the body 50 are preferably provided with the camming surfaces 58 of the same curvature, the radius of which increases from the point 59 to the point 60. The end of the body 50 may be provided with a flat surface 61.

The collar 16 has a pair of upwardly extending retaining flanges 62, which are joined by the bolt 63, and which extend parallel to each other, but are spaced sufficiently to receive the connecting rod 17.

The lower edge 64 of the flanges 62 is preferably straight and plane and adapted to engage the flat surface 61 on the ring body 50.

The arm 15 is preferably provided with a

diagonally upwardly extending portion 65 and a horizontally extending portion 66. The horizontally extending portion 66 may be provided with an enlargement 67, forming a pair of spaced bearings 68, 69 for a pintle 70, by means of which the arm 15 is connected to a connecting rod 17.

The connecting rod has a similar bearing portion 71, which fits between the bearing portions 68, 69. At its opposite end the arm 15 is provided with an enlargement or bearing portion 72, having a transverse bore 73 for receiving the screw bolt 74. At this end the collar 16 has its parts provided with a pair of substantially parallel flanges 75, which extend substantially horizontally.

Between the end flanges 16 and 75 the collars 16 are provided with partially spherical portions 76, which are of such curvature that they fit in the groove 21 of the insulator 12 so that this collar may be fixedly clamped on the insulator by means of the bolts 63 and 74.

The horizontal portion 66 of the lever 15 is preferably provided with a conductor-engaging shoe 77 of metal or other material. This shoe is fixedly secured to a threaded member 78, which may consist of a screw bolt, having its lower end threaded into a bore in the shoe 77.

The shoe may thus be pivotally mounted on the arm 15 with the head of the bolt 78 engaging the top of the arm and the bolt extending through a bore 79 in the arm.

The shoe 77 is preferably of substantial length so that its V groove 80 engages the conductor 81 over a substantial distance. This aids in maintaining the alignment of the shoe 77 with the conductor 81. The shoe may be supplied in metal closely related to the conductor material, such as, for example, a brass shoe may be used for copper conductors, and an aluminum shoe for aluminum conductors, a galvanized shoe for steel or aluminum conductors, etc. By this arrangement electrolytic corrosion between the shoe and the conductor is avoided.

Since the shoe is pivotally mounted on the arm 15, it may extend at any angle, and the collar 16 may be clamped diagonally on the insulator 12 with respect to the cross arm 11.

Thus the eye member 45 may extend out toward one side of the cross arm to be engaged conveniently by a clamp stick. This prevents the cross arm 11 from interfering with the operation of the clamp stick in actuating the eye.

The operation of this embodiment of the invention is substantially the same as that previously described, except that in this case there is a cam action at the surface 58 for tightening the arm 15 against the conductor, and the flat surface 61 serves as a latching surface for holding the device in latching position.

When a conductor is to be secured to an insulator and the device itself has already been mounted on the insulator by means of its collar 16, the conductor is placed in the insulator groove 20; and a clamp stick having been secured to the eye 45, the arm 15 is pulled down against the conductor so that its shoe engages the conductor 81.

The eye member 51 may be pivoted upward in a counterclockwise direction in Fig. 3 until the connecting rod 17 passes down between the flanges 62. Then a downward pull on the eye 45 will cause the camming surface 58 to slide against the lower edge portions of the flanges 62; and as the radius of the cam 58 increases, the connecting rod 17 will be pulled and the resilient

arm 15 drawn into tight engagement with the conductor 81, which will be forced against the insulator 12.

As the curved camming surface 58 passes out of engagement with the flanges 62, the flat portion 61 comes into engagement with the flanges 62, and the connecting rod 17 drops backward slightly, relieving the tension of the arm 15 slightly; but still maintaining it in tight engagement with the conductor and insulator.

The surface 61 on the eye member 51 serves as a latching surface, as it requires a definite force applied to the eye 45 in a clockwise direction to pivot this member upward from the position of Fig. 3. Thus there is a snap action in the release of the device of Fig. 3, as the eye member 51 pivots upward. There is also a snap action in the device of Fig. 2 as the eye member 41 is rotated and the stop members 46 are cammed out of the space between the flanges 62.

It will thus be observed that I have invented an improved conductor-insulator clamping device which is provided with an improved form of securing device that cannot possibly become loosened by vibration or by the application of force to the line or pole or insulator.

The present devices open and close with a snap action, and are definitely held in the closed position. The conductor is resiliently clamped on the insulator, but it may be removed at any time and as often as desired, without necessity for using a new clamp.

The expense incident to the destruction of an old tie wire and the use of a new one, in the removal of a conductor from an insulator, is entirely eliminated.

The present clamping devices may be so arranged on an insulator that the eye extends toward one side of the cross arm, where it may be more conveniently engaged by a clamp stick. The clamping device may be provided with conductor-engaging shoes of appropriate metal, depending on the metal used in the transmission line conductor.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In a conductor-insulator clamp for electric lines, the combination of clamping means adapted to be permanently secured in the peripheral groove of an insulator, with a resilient arm pivotally mounted in said clamping means and adapted to engage a line conductor carried by said insulator, a connecting rod pivotally secured to said arm, and securing means carried by said connecting rod and engaging said clamping means for urging said resilient arm into engagement with the conductor on said insulator, said arm having a pivoted shoe for engaging said conductor whereby the arm may be arranged diagonally with respect to the line to avoid interference between a cross arm and the line tools used on said clamp.

2. In a conductor-insulator clamp for electric lines, the combination of clamping means adapted to be permanently secured in the peripheral groove of an insulator, with a resilient arm pivotally mounted in said clamping means and

adapted to engage a line conductor carried by said insulator, a connecting rod pivotally secured to said arm, and securing means carried by said connecting rod and engaging said clamping means for urging said resilient arm into engagement with the conductor on said insulator, said arm having a pivoted shoe for engaging said conductor whereby the arm may be arranged diagonally with respect to the line to avoid interference between a cross arm and the line tools used on said clamp, said shoe having a longitudinally extending groove for engaging said line conductor.

3. In a conductor-insulator clamp for electric lines, the combination of clamping means adapted to be permanently secured in the peripheral groove of an insulator, with a resilient arm pivotally mounted in said clamping means and adapted to engage a line conductor carried by said insulator, a connecting rod pivotally secured to said arm, and securing means carried by said connecting rod and engaging said clamping means for urging said resilient arm into engagement with the conductor on said insulator, said securing means comprising a threaded member threadedly engaging said connecting rod, and said threaded member having latching elements drawn into engagement with said clamping means by said resilient arm.

4. In a conductor-insulator clamp for electric lines, the combination of clamping means adapted to be permanently secured in the peripheral groove of an insulator, with a resilient arm pivotally mounted in said clamping means and adapted to engage a line conductor carried by said insulator, a connecting rod pivotally secured to said arm, and securing means carried by said connecting rod and engaging said clamping means for urging said resilient arm into engagement with the conductor on said insulator, said securing means comprising a threaded member threadedly engaging said connecting rod, and said threaded member having latching elements drawn into engagement with said clamping means by said resilient arm, said threaded member having an eye formed therein for engagement with a clamp stick.

5. In a conductor-insulator clamp for electric lines, the combination of clamping means adapted to be permanently secured in the peripheral groove of an insulator, with a resilient arm pivotally mounted in said clamping means and adapted to engage a line conductor carried by said insulator, a connecting rod pivotally secured to said arm, and securing means carried by said connecting rod and engaging said clamping means for urging said resilient arm into engagement with the conductor on said insulator, said connecting rod having a threaded portion, a threaded eye member on said threaded portion for engaging said clamping means, and said clamping means having a pair of upwardly extending flanges for embracing said rod and engaging said threaded member.

6. In a conductor-insulator clamp for electric lines, the combination of clamping means adapted to be permanently secured in the peripheral groove of an insulator, with a resilient arm pivotally mounted in said clamping means and adapted to engage a line conductor carried by said insulator, a connecting rod pivotally secured to said arm, and securing means carried by said connecting rod and engaging said clamping means for urging said resilient arm into engagement with the conductor on said insulator, said connecting

rod having a threaded portion, a threaded eye member on said threaded portion for engaging said clamping means, and said clamping means having a pair of upwardly extending flanges for embracing said rod and engaging said threaded member, said threaded member having a latching shoulder adapted to be received between said flanges to prevent rotation of said threaded member under predetermined conditions.

10 7. In a conductor-insulator clamp, the combination of a pair of collar members of metal, said collar members each being provided with partially circular portions for engagement in the groove of a line insulator, and said collar members having laterally projecting securing flanges extending in substantially parallel position, a threaded member at each of the ends of said collar members, said threaded members passing through the collar members to secure them together on the line insulator, a conductor engaging arm pivoted on one of said threaded members and having securing means for engaging said collar members adjacent the other of said threaded members, said securing means comprising a threaded member provided with a shoulder for engagement between the flanges of said collar members.

15 8. In a conductor-insulator clamp, the combination of a pair of collar members of metal, said collar members each being provided with partially circular portions for engagement in the groove of a line insulator, and said collar members having laterally projecting securing flanges extending in substantially parallel position, a threaded member at each of the ends of said collar members, said threaded members passing through the collar members to secure them together on the line insulator, a conductor engaging arm pivoted on one of said threaded members and having securing means for engaging said collar members adjacent the other of said threaded members, said securing means comprising a threaded member provided with a shoulder for engagement between the flanges of said collar members, and said threaded member having an eye formed therein for engagement with a line tool.

20 9. In a conductor-insulator clamp, the combination of a cast metal insulator collar adapted to be secured in the groove of an insulator, said collar comprising a pair of metal members, each of said metal members having a partially circular portion and a laterally extending flange, said flanges extending parallel to each other at the opposite sides of said collar, two of said flanges being joined by a pivot member, and a resilient metal arm pivotally mounted on said pivot member and extending upward and over the top of the insulator, said arm having a pivoted grooved shoe located thereon to register with the upper groove in the insulator, irrespective of the rotative position of the collar on the insulator, a connecting rod pivotally mounted on said arm, and having a threaded end extending downward between the other two laterally projecting flanges on said collar, and a complementary threaded member provided with an integral eye adapted to be engaged by a clamp stick or the like threaded on the end of said connecting rod for drawing said arm downward into resilient engagement with the conductor in the insulator groove, said complementary threaded member having a thrust surface for engaging below the adjacent flanges on the collar and having a retaining lug adapted to be received between the flanges on the collar to

latch the threaded member in any of various predetermined positions.

10. In a conductor-insulator clamp for electric lines, the combination of clamping means adapted to be permanently secured in the peripheral groove of an insulator, with a resilient arm pivotally mounted in said clamping means and adapted to engage a line conductor carried by said insulator, a connecting rod pivotally secured to said

5 arm, and securing means carried by said connecting rod and engaging said clamping means for urging said resilient arm into engagement with the conductor on said insulator, said securing means comprising a threaded member threadedly engaging said connecting rod, said threaded member having an eye formed therein for engagement with a clamp stick.

DAVID C. HUBBARD.
